INVENTOR
HERMAN L. GREVE.

BY *Frank M. Shiley*
ATTORNEY

UNITED STATES PATENT OFFICE.

HERMAN L. GREVE, OF BROOKLYN, NEW YORK, ASSIGNOR TO THE INTERNATIONAL MAILING TUBE & WRAPPER COMPANY, OF BROOKLYN, NEW YORK.

MAILING WRAPPER.

Application filed March 18, 1922. Serial No. 544,320.

To all whom it may concern:

Be it known that HERMAN L. GREVE, a citizen of the United States, and a resident of New York city, in the borough of Brooklyn, in the county of Kings and State of New York, has invented certain new and useful Improvements in Mailing Wrappers, of which the following is a specification.

My invention relates to packages and especially to that class of packages in which a wrapper is used which is adapted to be used in transporting articles by express or mail.

The object of my invention is to provide a wrapper for holding perishable products such as freshly cut flowers, young plants such as cabbage plants, strawberry plants, etc. raised by plant growers and retailed to small home gardeners or articles which would be injured by moisture, in fact a water proof or semi water proof wrapper which comprises a stiff casing to prevent the contents being crushed and a comparatively thin and practically water proof lining sheet which incloses the contents as well as the stiff casing when the package is complete. In view of the stiff quality of the casing portion my invention discloses a way by which the same is formed in order that it may be wrapped about the contents of the package without the use of tools.

A further object of my invention is to provide a wrapper that can be lengthened by combining a number of wrapper units to form the complete package of the desired length.

Referring to the drawings which form a part of this invention,

Figure 1 is a perspective view of a wrapper made in accordance with my invention.

Figure 2 is an end view.

Figure 3 is a perspective view of a package illustrating two units joined to provide a wrapper of greater length than that of a single unit.

Figure 4 is a perspective view illustrating the appearance of the wrappers when prepared for sale by the user or retailer.

My wrapper comprises two parts, a stiff casing portion A and a comparatively flexible wrapping portion B made of water proof or nearly water proof material such as tough paper having a coating or lining of material of non-hygrosopic material that is

practically water proof for the purpose described. This coating which extends entirely over the inner surface of the sheet B may be made of rubber dissolved in gasoline which sets and forms a tough flexible coating when the solvent has evaporated, or may be of any other suitable material. The two portions A and B are cemented together by a suitable gum D which entirely covers the surface of portion A adjacent portion B. After the portions have been cemented together with the casing portion on the outside of portion B, the wrapper is bent into a curved form illustrated in Figures 1 and 2 by passing it between rollers similar to those used in forming stove pipe, thus giving it the required form.

I prefer to make the casing A of stiff cardboard material as it is light in weight and cheap in cost.

It will be observed that the portion B extends beyond the ends of the portion A at the sides and top, the top portion B' being wrapped over the portion A to a more or less extent depending on the bulk of the contents wrapped.

In Figure 3 a package is shown comprising two wrapper units C and C' respectively. When used in this way the adjacent ends of the two units are placed together in overlapping relation as indicated at D and D' resting within the end of the casing portion of unit C and the end D resting over the adjacent end of the casing portion of the unit C' and thus when the two units are wrapped together over the contents of the package they are held snugly together, and may further be secured by a longitudinally extending cord E if desired.

In use, the contents such as freshly cut flowers are laid in the space F and the wrapper rolled into cylindrical form thereover, thus bringing the water proof lining in close contact and thereafter the ends G—G respectively are tucked within the casing portion A thus completely inclosing the contents. The water proof qualities of the wrapper thus prevent evaporation of the moisture of the flowers and at the same time prevent any moisture from same injuring any other mail matter with which it may be in contact.

It is obvious that delicate silks, laces, etc. may be mailed in this wrapper with com-

parative safety from injury by reason of of, and having a flap portion adapted to be contact with other mail packages in transit. wrapped over said casing. 30

Having thus described my invention I claim as new:

5. 1. A mailing wrapper comprising an outer casing of curved form adapted to be rolled into cylindrical form and an inner sheet secured thereto having a water resisting component the relative sizes of said 10 sheets being such that said inner sheet is adapted to be rolled over the outer surface of said casing.

2. A mailing wrapper comprising an outer casing of curved form adapted to be 15 rolled into cylindrical form and an inner sheet having a water resisting component and being of such size as to be adapted to be rolled over the outer surface of said casing, said sheet being cemented to said casing. 20

3. A mailing wrapper comprising an outer casing of curved form adapted to be rolled into cylindrical form and an inner sheet having a water resisting component 25 and of such size as to be adapted to be rolled over the outer surface of said casing, said sheet being cemented to said casing and extending beyond the same at each end there-

4. A mailing wrapper comprising a plurality of units each having an outer casing of curved form adapted to be rolled into cylindrical form and an inner sheet secured to said outer casing said inner sheet having a water resisting component and of such size as to be adapted to be rolled over the outer surface of said casing. 35

5. A mailing wrapper comprising a plurality of units each having an outer casing of curved form adapted to be manually rolled into cylindrical form and an inner sheet having a water resisting component secured to said outer casing, and of such size as to be adapted to be rolled over its respective casing, the end portion of one unit being interrolled with that of its adjacent unit to provide a wrapper of greater length than that of a single unit. 40

Signed at Brooklyn, in the county of 50
Kings and State of New York this 15th day
of March A. D. 1922.

HERMAN L. GREVE.
